US00D613008S

(12) United States Design Patent
Ullmann

(10) Patent No.: US D613,008 S
(45) Date of Patent: * Mar. 30, 2010

(54) CLEANING DEVICE FOR AN ELECTRIC SHAVER

(75) Inventor: Roland Ullmann, Offenbach (DE)

(73) Assignee: Braun GmbH, Kronberg (DE)

() Term: 14 Years

(21) Appl. No.: 29/308,313

(22) Filed: Jun. 10, 2008

(30) Foreign Application Priority Data

Dec. 10, 2007 (DE) 4 07 06 067

(51) LOC (9) Cl. 15-05

(52) U.S. Cl. D32/1

(58) Field of Classification Search D32/1, D32/5; 30/537-538; D28/44, 73-74; 134/135
See application file for complete search history.

(57) CLAIM

The ornamental design for a cleaning device for an electric shaver, as shown and described.

DESCRIPTION

FIG. 1 is a perspective view of a cleaning device for an electric shaver from above, showing my new design;

FIG. 2 is a front view thereof;

FIG. 3 is a side view thereof;

FIG. 4 is a an opposite side view thereof;

FIG. 5 is a rear view thereof;

FIG. 6 is a top plan view thereof; and,

FIG. 7 is a bottom plan view thereof.

The broken line showing of details in FIGS. 4-6 is included for the purpose of showing environmental portions of the cleaning device for an electronic shaver and forms no part of the claimed design.
